(57) **CLAIM**

The ornamental design for a computer, as shown and described.

DESCRIPTION

FIG. 1 is a top, front, right-side perspective view of a computer in accordance with our new design;

FIG. 2 is a front elevational view of the computer shown in FIG. 1;

FIG. 3 is a rear elevational view of the computer shown in FIG. 1;

FIG. 4 is a right-side elevational view of the computer shown in FIG. 1;

FIG. 5 is a left-side elevational view of the computer shown in FIG. 1;

FIG. 6 is a top plan view of the computer shown in FIG. 1;

FIG. 7 is a bottom plan view of the computer shown in FIG. 1;

FIG. 8 is a top, front, right-side perspective view of the computer shown in FIG. 1 in an open configuration;

FIG. 9 is a top elevational view of the computer shown in FIG. 1 in an open configuration; and

FIG. 10 is top, rear, right-side perspective view of the computer shown in FIG. 1; and,

FIG. 11 is an enlarged view of the corner of the computer shown in broken lines in FIG. 10.

The broken lines represent portions of the computer that form no part of the claimed design.

1 Claim, 8 Drawing Sheets
